UNITED STATES PATENT OFFICE.

CHARLES SELKIRK, OF ALBANY, NEW YORK, ASSIGNOR TO BENJAMIN MARSH
AND FREDERICK W. HOFFMAN, BOTH OF SAME PLACE.

DESIGN FOR A SPOON.

SPECIFICATION forming part of Design No. 20,929, dated July 7, 1891.

Application filed March 10, 1891. Serial No. 384,493. Term of patent 3½ years.

To all whom it may concern:

Be it known that I, CHARLES SELKIRK, a citizen of the United States, residing at Albany, in the county of Albany and State of New York, have invented certain new and useful Improvements in Designs for Spoons; and I do hereby declare the following to be a full, clear, and exact description of the invention, such as will enable others skilled in the art to which it appertains to make and use the same.

The accompanying drawing illustrates my design for spoons.

In this design the main figure entering into the handle of the spoon is an Indian canoe-paddle A, which bears on its blade the figure a of an Indian kneeling and drinking from his hand. The handle a' of this paddle extends down from its blade to the bowl F of the spoon. In some cases the figure of a quiver B of arrows is displayed back of the blade of the paddle. With this figure of the canoe-paddle are the Indian bows C C, which cross each other and the handle a' of said

paddle at about midway between the paddle-blade and the bowl of the spoon. In some cases these bows crossing each other and the handle may be omitted. The strapping b of the quiver is represented as being twined around the crossed bows and handle of the paddle. At the juncture of the bowl F with the handle is the figure D of a land-tortoise.

What I claim is—

The design for a spoon herein described and shown, the same comprising the figure A of a canoe-paddle having on its blade the figure a of a kneeling Indian drinking from his hand, and the figure D of a land-tortoise at the juncture of the handle with the bowl F, as set forth.

In testimony that I claim the invention above set forth I affix my signature in presence of two witnesses.

CHARLES SELKIRK.
